UNITED STATES PATENT OFFICE.

ORVILLE P. NORMAN, OF LOS ANGELES, CALIFORNIA.

RECIPROCATING MOVEMENT.

Application filed July 14, 1923. Serial No. 651,623.

To all whom it may concern:

Be it known that I, ORVILLE P. NORMAN, a citizen of the United States, and resident of Los Angeles, in the county of Los Angeles and State of California, have invented new and useful Improvements in Reciprocating Movement, of which the following is a specification.

This invention relates to a mechanical movement for transforming rotary into reciprocating movement and pertains to the type of movements disclosed in United States Letters Patent 1,210,353, granted to me December 26, 1916, and 1,268,048, granted to me May 28, 1918. The present invention is a device of the same character but much simplified and changed in detail.

The movement shown herein comprises a reciprocable carriage having racks disposed to be engaged alternately with oppositely rotating gears, and mechanism actuated by the carriage whereby the proper racks are engaged with the proper gears at the ends of their movements. The objects of this invention are to provide a movement of the character described having details of structure whereby to accomplish the above mentioned objects and to positively lock the parts in engaged position during their operative periods.

These objects together with other objects and corresponding accomplishments are obtained by means of the embodiment of my invention illustrated in the accompanying drawing, in which:

Fig. 1 is a front elevation of the movement; Fig. 2 is an elevation in section as seen on the line 2—2 of Fig. 3; Fig. 3 is a cross section as seen on the line 3—3 of Fig. 1; Fig. 4 is a fragmentary detail view in elevation of a portion of the locking mechanism in a position different from that shown in Fig. 2; Fig. 5 is a fragmentary view in elevation showing a fragment of the bridge and the locking mechanism in another position; Fig. 6 is a fragmentary cross section similar to that shown in Fig. 3 with the parts in position to move the carriage in the opposite direction to that in which it is being moved in Fig. 3; Fig. 7 is a fragmentary view in elevation of one end of the structure with parts broken away to show the abutment mechanism; Fig. 8 is a view indicating positions of the bridge elevating mechanism; Fig. 9 is a transverse section through the table showing the neutral lock;

and Fig. 10 is a plan view of the table showing a fragment thereof and the neutral lock.

Referring more particularly to the drawing, A indicates the frame or bed upon which is slidably mounted the reciprocating carriage B. The drive mechanism is indicated generally by C. Arrows in the several figures indicate the direction of travel of the parts.

The frame A comprises pairs of legs 15 and 16, the pairs being suitably spaced and shown herein as formed of angle bars. The front pair of legs 15 are longer than the rear and mounted thereon is an angle bar 17. Mounted upon the top of legs 16 at a lower level is an angle bar 18. The legs and angle bars are so spaced as to leave a well between them. Mounted upon angle bar 18 is a T-bar 19 forming a rail for the table. Mounted upon angle bar 17 is an angle bar 20 having an extension 21 inclined thereto and forming a rail for the table.

The table comprises a plate 22 provided with an angle bar 23 overhanging rail 19. 80 Bracket straps 24 extend downwardly and journalled thereon are rollers 25 riding against the lower edge of rail 19. Mounted on the bar 23 above the rail 19 are rollers 26. On the under side of the table in alignment 85 are guides 27. These guides are blocks having recesses conforming to the shape of rail 21. Pintles 28 secured to the table have mounted thereon rollers 29 which underhang the rail 21.

Mounted upon the upper leg of angle bar 18 of the frame is a bridge 30. Bridge 30 has at its far end an angular pin 31 fitting in a corresponding recess in a block 32 mounted upon bar 18, see Fig. 2. This articulation permits the bridge to be tilted by raising and lowering the forward end. The forward end of bridge 30 has depending therefrom an extension 33 with spaced laterally projecting lugs to receive the ends of 100 a trip lever. A rack bar 34 is provided on its under surface with rollers 35 riding on bridge 30. The vertical leg of the bridge is disposed in the well on the frame. A rack 36 mounted on the bar is provided with 105 teeth on its lower side. This rack is at the rear of bar 34. At the forward side of the bar 34 is a bevel rack 37. A roller 38 engages the bar 17 and a roller 39 journalled on bar 34 engages bar 18 to assist in maintaining the bar 34 in proper position during 110 its travel.

Secured to the frame is a block 40 serving as a bearing for a shaft 41. A similar bracket 42 mounted on the other side of the frame serves as a bearing for the opposite 5 end of the shaft. Fixed to the shaft 41 is a bevel gear 43. Bevel gear 43 meshes with a bevel pinion 44 journalled on angle bar 17. The bevel pinion is disposed to be engaged with the bevel rack 37 at the proper time. 10 Mounted upon the shaft 41 so as to rotate therewith is a spur pinion 45. This gear is disposed to engage the rack 36 at the proper time. Extending between the legs 15 is a bar 46 having journalled therein a 15 shaft 47 which is geared to a prime mover of some sort, not shown herein. A bevel pinion 48 is mounted upon shaft 47 and meshes with bevel gear 43 so that rotation of the shaft 47 will cause pinions 44 and 45 20 to rotate.

It will be noted that the plate 22 of the carriage clears the bar 34. At the far end of bar 34 on its upper surface is a projection 49 having a transverse depression or 25 slot. Mounted upon the bed plate 22 on the under side is a bifurcated bracket section 50, see Figs. 9 and 10 to which is pivotally secured a bracket catch 51. The catch is disposed to enter the depression in keeper 49 and extends through a slot in the bed plate 22. It is provided with a head 52 which limits the movement of the catch. The catch when free may gravitate to the 30 position shown in Fig. 9 and enter the keeper depression. The sides of the keeper are inclined so that as the table is moved with respect to the bar, the catch will ride upwardly over the edge of the keeper and into the depression. Secured to the bed plate adjacent the catch is a bracket 53. The bracket 53 has pivotally mounted therein a lift lever 54. The lever 54 is provided with a crank end disposed beneath the head 52 of the catch. By raising the handle of lever 54 to vertical position, the latch 51 is raised and held so that it will not engage the keeper 49 and the table is disengaged from the rack bar, placing the carriage in neutral position.

By referring especially to Figs. 5 and 6, 35 it will be noted that by raising and lowering the end of bridge 30, the rack bar 34 is elevated and depressed so that when in its lower position rack 36 is in mesh with gear 45 and when the bar is in its upper position, rack 37 is in mesh with pinion 44. Assume that the shaft 41 is rotating in 40 a clockwise direction. When bridge 30 and bar 34 are in their lower position with rack 36 in mesh with pinion 44, the carriage will move to the right. When bridge 30, bar 34 and rack 37 are in their upper position, rack 37 will be in mesh with bevel pinion 44 and the carriage will move to the left. In either 45 of these positions only one rack is in mesh with the driving gears. Pivotally mounted

upon the frame is a lift lever 55. The rear end of lever 55 is disposed between the lugs on bracket 33. When the bridge 30 is in its lower position, lever 55 will be horizontal. When the far end is swung downwardly to the position shown in Fig. 5, bridge 30 will be raised. Pivotally mounted in a bracket 56 of the frame is a lock latch 57. The latch has an extension or trigger portion 58 adapted to enter a corresponding recess in the bracket 33 when the bridge is raised. This position is shown in Fig. 5. A weight on the end of the catch tends to hold the latter in the position shown in Fig. 5. A lever 60 is mounted on the bracket, see Fig. 2, and is connected by a link 61 to the lock latch so that the latter may be tripped by operation of the lever. Pivotally mounted upon the frame at the other end of lever 55 is a lock latch having a finger 62 adapted to be disposed beneath the end of lever 55 at the proper time. This latch has a weight 63 tending to hold it in the position shown in Figs. 2 and 5. A finger 64 extends from the latch so as to be operated by a cross-over lever. The cross-over lever comprises an arm having an elongated slot in which is disposed a pin 65, the latter serving as a pivot pin for the lever. The arm 66 of the lever is rounded on its upper end. On the rear of the lever is a projection 67, see Fig. 8, adapted to be engaged with a pin 68 mounted on the frame. The other end of the cross-over lever is weighted as indicated by 69, tending to maintain the cross-over lever in the position shown in Fig. 5. Extending to the front of the lever is a pin 70. It will be noted that arm 66 is disposed to engage the finger 64 as shown in Fig. 4, and its teeth are engaged with pinion 45. A 105 guard embracing the cross-over lever is indicated by 71 and holds the latter against lateral displacement. Depending from the bar 34 is a hook 72 arranged to engage the pin 70 as shown in Fig. 5. Slidably mounted upon the frame A is a trip rod 73, best shown in Fig. 7. The trip rod is bent back upon itself as indicated by 74 and hooks about lever 60.

Referring to Fig. 7, if the hook rod 73 is moved to the right, lever 60 will be swung outwardly actuating the latch 57. The trip rod is disposed just below the bed plate 22, and adjustably mounted thereon is an abutment collar 75 serving as an abutment for the bed plate. The collar may be secured in any desired position by means of a set screw 76. Referring to Fig. 1 it is obvious that the table in its movement to the left will engage the abutment and move lock latch 57. When the table or carriage is moving to the left the bridge 30 is in its upper position and lock latch 57 is in the position shown in Fig. 5 locking the bridge in its upper position. A pull upon the link 61 will cause 120 125 130

the lock latch trigger 58 to be pulled out of the recess in bracket 33 and the latter can then drop to its lower position. Finger 62 of the latch at the opposite end will be moved by a weight 63 so as to be disposed beneath the lever 55 in the position shown in Fig. 2. The bridge is then locked in its horizontal position. Dropping of the bridge drops the bar 34 and rack 36 meshes with pinion 45 as shown in Fig. 3. The carriage then moves to the right. At the end of its travel to the right hook 72 engages pin 70 pushing the cross-over lever arm 66 toward pinion 45 causing it to mesh with the latter as shown in Fig. 4. The movement of the lower end of lever arm 66 causes it to engage finger 64 and pull finger 62 from beneath the bottom of the lever 55 as shown in Fig. 4. Movement of the pinion 45 raises the arm 66 causing the upper end of it to engage the end of rack 36 and to lift the bridge. The projection 67 rides over pin 68 maintaining the lever 66 in engagement with the pinion 45. This causes the parts to be disposed in the position shown in Fig. 6 with bevel rack 37 in mesh with gear 44 and the table moves to the left. The projection 67 rides over the top of pin 68 and the parts drop to the position shown in Fig. 2. The carriage then moves to the left. The table abuts the collar 75 moves the trip rod 73, lever 60, and link 61 to pull latch 57 out of engagement with extension 33 and releases the bridge which lowers engaging rack 36 with pinion 45.

What I claim is:

1. A mechanical movement comprising the combination of a frame, a carriage slidably mounted thereon and having a pair of racks secured thereto, a pair of pinions geared to rotate in opposite directions and disposed so that either will mesh with its corresponding rack, and thereby move said carriage, and means operated by said carriage at the ends of its travel to alternately engage one rack with its pinion and then the other whereby to reciprocate the carriage.

2. A mechanical movement comprising the combination of a frame, a carriage slidably mounted thereon and having a pair of racks secured thereto, a pair of pinions geared to rotate in opposite directions and disposed so that either will mesh with its corresponding rack and thereby move said carriage, and means operated by said carriage at the ends of its travel to alternately engage one rack with its pinion and then the other whereby to reciprocate the carriage, one of said means being an adjustable abutment whereby the distance of travel may be controlled.

3. In a mechanical movement the combination of a frame, a carriage comprising a bridge mounted thereon so as to be elevated or depressed, a rack bar carrying a pair of

racks slidably mounted on said bridge, a pair of pinions mounted on said frame and disposed so that in elevated position of the bridge one pinion engages a rack and in depressed position of said bridge the other pinion engages the other rack, said pinions being geared to rotate in opposite directions, a carriage plate slidably mounted on said frame and engaged with said rack bar so as to be moved therewith, and means operated by said carriage at the ends of its travel to alternately engage one rack with its pinion and then the other whereby to reciprocate the carriage.

4. In a mechanical movement the combination of a frame, a carriage comprising a bridge mounted thereon so as to be elevated or depressed, a rack bar carrying a pair of racks slidably mounted on said bridge, a pair of pinions mounted on said frame and disposed so that in elevated position of said bridge one pinion engages a rack and in depressed position of said bridge the other pinion engages the other rack, said pinions being geared to rotate in opposite directions, a plate slidably mounted on said frame and engaged with said rack bar so as to be moved therewith, and means operated by said carriage at the ends of its travel to alternately engage one rack with the pinion and then the other whereby to reciprocate the carriage, one of said means being an adjustable abutment whereby the distance of travel of the carriage may be controlled.

5. In a mechanical movement the combination of a frame, a carriage comprising a bridge articulated to said frame so that one end thereof may be tilted, a rack bar carrying a pair of racks slidably mounted on said bridge, a pair of pinions mounted on said frame and disposed so that in elevated position of said bridge one pinion engages a rack and in depressed position the other pinion engages the other rack, said pinions being geared to rotate in opposite directions, a plate slidably mounted on said frame and engaged with said rack bar so as to be moved therewith, and means operated by said carriage at the ends of its travel to alternately elevate and depress said bridge whereby to reciprocate said carriage.

6. In a mechanical movement the combination of a frame, a carriage comprising a bridge articulated to said frame so that one end thereof may be tilted, a rack bar carrying a pair of racks slidably mounted on said bridge, a pair of pinions mounted on said frame and disposed so that in elevated position of said bridge one pinion engages a rack and in depressed position the other pinion engages the other rack, said pinions being geared to rotate in opposite directions, a plate slidably mounted on said frame and engaged with said rack bar so as to be moved therewith, and means operated by

said carriage at the ends of its travel to alternately elevate and depress said bridge whereby to reciprocate said carriage, one of said means being an adjustable abutment whereby the distance of travel of the carriage may be controlled.

7. In a mechanical movement the combination of a frame, a carriage comprising a bridge articulated to said frame so that one end thereof may be tilted, a rack bar carrying a pair of racks slidably mounted on said bridge, a pair of pinions mounted on said frame and disposed so that in elevated position of said bridge one pinion engages a rack and in depressed position the other pinion engages the other rack, said pinions being geared to rotate in opposite directions, a plate slidably mounted on said frame and engaged with said rack bar so as to be moved therewith, means actuated by said carriage at one end of its travel to elevate said bridge, means to lock said bridge in elevated position, means actuated by said carriage at the opposite end of its travel to release said bridge and cause depression thereof, and means to lock said carriage in depressed position.

8. In a mechanical movement the combination of a frame, a carriage comprising a bridge articulated to said frame so that the ends thereof may be tilted, a rack bar carrying a pair of racks slidably mounted on said bridge, a pair of pinions mounted on said frame and disposed so that in elevated position of said bridge one pinion engages one rack and in depressed position the other pinion engages the other rack, said pinions being geared to rotate in opposite directions, a plate slidably mounted on said frame and engaged with said rack bar so as to be moved therewith, means actuated by said carriage at one end of its travel to elevate said bridge, means to lock said bridge in elevated position, abutment means actuated by said carriage at the opposite end of its travel to release said bridge and cause depression thereof, said abutment means including an adjustable abutment whereby to control the distance of travel of said carriage, and means to lock said carriage in depressed position.

9. In a mechanical movement the combination of a frame, a carriage comprising a bridge mounted upon said frame so as to be elevated or depressed, a rack bar carrying a pair of racks slidably mounted on said bridge, a pair of pinions mounted on said

frame and disposed so that in elevated position of said bridge one pinion engages a rack and in depressed position of said bridge the other pinion engages the other rack, said pinions being geared to rotate in opposite directions, a plate slidably mounted on said frame, manually operable means to engage said plate with said rack bar so that the latter will be moved therewith, means operated by said carriage at the ends of its travel to alternately engage one rack with its pinion and then the other whereby to reciprocate the carriage.

10. In a mechanical movement the combination of a frame, a carriage comprising a bridge articulated to said frame so that one end thereof may be tilted, a rack bar carrying a pair of racks slidably mounted on said bridge, a pair of pinions mounted on said frame and disposed so that in elevated position of said bridge one pinion engages one rack and in depressed position of said bridge the other pinion engages the other rack, said pinions being geared to rotate in opposite directions, a plate slidably mounted on said bridge, manually operable means for engaging said plate with said rack bar so as to move the latter therewith, means operated by said carriage at the ends of its travel to alternately engage one rack with its pinion and then the other whereby to reciprocate the carriage, one of said means being an adjustable abutment whereby the distance of travel may be controlled.

11. In a mechanical movement the combination of a frame, a carriage comprising a bridge articulated to said frame so that one end thereof may be tilted, a rack bar carrying a pair of racks slidably mounted on said bridge, a pair of pinions mounted on said frame, and disposed so that in elevated position of said bridge one pinion engages a rack and in depressed position the other pinion engages the other rack, said pinions being geared to rotate in opposite directions, a plate slidably mounted on said frame, manually operable means for engaging said plate with said rack bar so as to be moved therewith, means operated by said carriage at the end of its travel to alternately raise and depress said bridge whereby to engage one rack with its pinion and thereby to reciprocate said carriage.

In witness that I claim the foregoing I have hereunto subscribed my name this 7th day of July, 1923.

ORVILLE P. NORMAN.
